Ross Egerton Browne

UNITED STATES PATENT OFFICE.

ROSS EGERTON BROWNE, OF SAN FRANCISCO, CALIFORNIA, ASSIGNOR TO
THE FRASER & CHALMERS, LIMITED, OF LONDON, ENGLAND.

MEANS FOR RAISING WATER FROM MINE-SHAFTS, &c.

SPECIFICATION forming part of Letters Patent No. 628,219, dated July 4, 1899.

Application filed January 10, 1899. Serial No. 701,768. (No model.)

To all whom it may concern:

Be it known that I, ROSS EGERTON BROWNE, a citizen of the United States, and a resident of San Francisco, California, but temporarily residing in London, England, have invented 55 Improved Means for Raising Water from Mine-Shafts or other Places, of which the following is a specification.

In sinking a pit or shaft into the ground

- 10 the surface or other water which collects therein is now generally lifted and delivered to the surface by various kinds of pumps, which the miner commonly calls "sinking-pumps." Usually these are suction and force
- 15 pumps with reciprocating pistons and plungers operated by steam, compressed air, electric motors, or by rods actuated by machinery on the surface. The pump is usually placed in the shaft, generally fifteen to twenty-five
- 20 feet above its bottom, and draws the water by suction through a strainer and suction-hose to the pump-cylinder, whence the reciprocating piston or plunger forces it upward by direct action to any desired elevation. It is
- 25 not practicable to provide more than a very small pump in the bottom of the shaft while the work of sinking is in progress, and the pump must adapt itself to drafts of water, mud, sand, small rock, fragments, and air
- 30 without serious interference with its operation. The pump must be lowered from time to time as the work progresses, the power-supply and water-discharge pipes must be extended and new connections made, and at
- 35 times of breaking the rock in the shaft-bottom by blasting the pump must either be lifted away to a safe point or protected by a bulkhead of heavy timbers.

There result frequently serious losses of 40 time in handling the pump, packing, and repairing its rapidly-wearing parts. In sinking a deep shaft in wet ground the extraction of the water is notoriously a source of material delay.

45 After a shaft is completed and a deep pump provided bailing-tanks are frequently used to lower into the water and hoist it to the surface; but during the progress of the sinking of the shaft a sufficient sum to dip from can-

55 According to the present invention it is proposed to utilize what may be called a combination of the vacuum system of pumping with the bailing system of raising the water, and in order that the invention may be clearly understood reference is made to the accompanying drawing, which indicates one form of apparatus for carrying the invention into practice.

In said drawing, A indicates a vacuum- 60 tank or bailing vessel provided with a suction-valve B, suction-hose C, and strainer and foot-valve D, the tank being also provided with a discharge-valve E, operated by a rod F and lever G in a manner hereinafter described. Vacuum is produced in the tank A by means of a vacuum-producer H on the surface, which is connected with the tank by vacuum-pipe I and coupling J. The tank travels on guides in the shaft and is raised 7c and lowered in the ordinary way by rope K and motor L.

The operation of the apparatus is as follows: The vacuum-tank is lowered to a point near to the bottom of the shaft, and the water is drawn into the tank by virtue of the vacuum or partial vacuum therein. When the tank is filled or partially filled with water, the coupling J is disconnected and the tank is hoisted to the surface to the position shown 80 by dotted lines, when the outer end of lever G will come in contact with stationary trip M and open valve E, permitting the discharge of the water through trough N, after which the tank, emptied of its water, is returned to 85 the bottom of the shaft and reconnected with the vacuum-pipe, and the operation is repeated.

The coupling J may be connected with the vacuum-pipe either rigidly or preferably by 90 means of a flexible hose and is most suitably constructed to cut off the air-intake when uncoupled and open the same when coupled. As the shaft increases in depth fresh lengths of rigid pipes I would be added.

95 Ordinary dipping and dumping tanks are of course well known; but these are not adapted for use except there is a considerable depth of water in the shaft, and consequently they cannot keep a shaft even comparatively 100

dry, while direct-acting pumps are subject to much wear when dealing with water, mud, sand, and the like, while the present apparatus will lift air, water, mud, and sand with less than the usual amount of wear and tear, and it also necessitates less labor in handling and repairing, is more easily kept in order, and is more reliable in its action than the sinking-pumps in ordinary use.

10. What I claim is—

In an apparatus for raising water from mines or shafts, the combination of a frame at the head of a shaft, a tank supported upon the frame adapted to be raised and lowered 15 in the shaft, said tank having a suction-pipe, and a valve-controlled discharge-opening at

its lower end, a vacuum - generator at the shaft-head, an adjustable pipe connecting the generator with the tank, hoisting mechanism for raising and lowering the tank, and means 20 for automatically opening the discharge-opening of the tank when the same reaches the discharge-point in its upward movement, substantially as described.

In testimony whereof I have hereunto set 25 my hand in the presence of two subscribing witnesses.

ROSS EGERTON BROWNE.
